UNITED STATES PATENT OFFICE.

JOSEPH MARION, OF BROOKLYN, NEW YORK.

OIL-STOVE.

SPECIFICATION forming part of Letters Patent No. 278,574, dated May 29, 1883.

Application filed September 6, 1882. (Model.)

To all whom it may concern:

Be it known that I, JOSEPH MARION, of the city of Brooklyn, in the county of Kings and State of New York, have invented certain new and useful Improvements in Oil-Stoves, of which the following is a full, clear, and exact description.

My invention consists, principally, of an open bottom or tray to be placed inside of the stove, and upon which is to be placed asbestos fiber or similar material, to which the oil is supplied for burning. The supply of oil to the asbestos on the tray is regulated by the weight of the oil on the tray by means of a valve and counterbalance-weight placed under the tray, and a water-tank is provided, through which the oil passes from the reservoir to the tray, which effectually seals the pipe and prevents any flow of gas to the tray; and these features also constitute parts of my invention.

My invention further consists of the construction, arrangement, and combination of parts, all as hereinafter fully described.

Reference is to be had to the accompanying drawings, forming part of this specification, in which similar letters of reference indicate corresponding parts in all the figures.

Figure 1 is a sectional elevation of my invention. Fig. 2 is a broken plan view of the tray; and Fig. 3 is a sectional elevation of the tray, taken on the line $\alpha\alpha$ of Fig. 1.

The stove A may be of any suitable form and size, and the elevated reservoir B may be of any suitable size, and may be located at any convenient part of the room a proper distance away from the stove. The pipe C, leading from the reservoir to the stove, is connected to the tank D, placed under the stove, and this tank is to be kept filled with water to a point above the short pipe a. Coupled to the short pipe b, at the top of the tank, is the pipe E, which is reduced in size at its upper end, as shown at e. Leading from the larger portion, e', of this pipe are the branch elbow-pipes F, which pass up through the collared openings g g of the tray G, and working in this larger portion, e', of the pipe is the valve h, the stem h' of which reaches up through the smaller portion, e, and is attached to and within the cap j, secured to the bottom of the tray G, so that any vertical movement of the tray will be communicated to the valve h, thus opening

or closing the pipes F F, according to the movement of the tray. The tray G is placed loosely upon the upper end, e, of the pipe E, the pipe entering the cap j, as shown, and the tray rests upon the collar H, placed upon the pipe, which collar rests upon the short arm of the lever J. The outer end of this lever is provided with the weight K, which counterbalances the tray G, and this weight is made adjustable by means of the screw k, by which it may be so set that the stove will be self-regulating as to the flow of oil. The bottom of the tray is preferably corrugated or bent, so as to form the upward swells c c, side pockets or troughs, d d, and the central pocket, d'. In the pockets d d and d' are to be placed suitable quantities of asbestos fiber, as shown at l l, Fig. 3, and through the swells c c are formed the series of perforations i i, through which air passes to support the combustion of the oil. The upper ends of the pipes F F are provided with the distributors f f, which distribute the oil as it flows from the said pipes F F to all parts of the tray.

In use, the weight K being properly set to hold the tray elevated and the pipes F F open, the cock m of the pipe C is to be opened to admit the oil to the reservoir D. Entering the reservoir, the oil passes up through the water therein, thence up through the pipes E and F, and onto the tray G, saturating the asbestos in the troughs d d and d'. The flow of oil will continue until the weight of oil on the tray, together with the weight of the tray, overbalances the weight K, whereupon the tray will move slightly downward, causing the valve h to close the pipes F F, and thus cut off the flow of oil. The oil being now lighted, the tray will remain in this downward position until the weight of oil on the tray is slightly reduced, whereupon the weight K will slightly lift the tray, and thus permit the oil to flow, supplying the oil to the tray only as fast as it is consumed. In this manner it will be seen that the stove regulates its own supply of oil, that the weight K may be set so that the flow of oil will be rapid or slow, according to the amount of heat required, and that the heat will be regular. The asbestos serves as a wick to the flame, and, being non-combustible, overcomes the annoyance and expense of renewing the wicks. Besides, the stove is per-

fectly safe, since any gas that might accumulate in the reservoir is effectually prevented from entering the stove by the water in the tank D, and the tray G may be placed in the fuel-chamber of any ordinary stove or fire-place.

Instead of using one lever J and one adjustable weight K, as shown in the drawings and as above described, two such levers and weights could be used—one upon each side of the stove—and not depart from the spirit of my invention.

I do not confine myself to the use of my invention for household purposes, as I design to use it also for heating all kinds of steam-boilers.

Having thus described my invention, what I claim as new, and desire to secure by Letters Patent, is—

1. In an oil-stove, the combination, with the supply-pipes F, of the tray G, the counterbalance-weight K, and the valve h, substantially as and for the purpose set forth.

2. The pipe E and branch pipes F, in combination with the vertically-movable tray G and valve h, substantially as and for the purposes set forth.

3. The combination, with the movable tray G, of the lever J, adjustable weight K, pipes E and F, and valve h, attached to the tray, substantially as and for the purposes set forth. 30

4. The combination, with the tray G and lever J and pipe E, of the collar H, placed upon the pipe E, between the short arm of the lever and the bottom of the tray, substantially as and for the purposes set forth. 35

5. In an oil-stove, the combination, with the counterbalanced tray G, provided with collared openings g, and the valve h, of the pipes F, provided with the distributors f, substantially as and for the purpose set forth. 40

6. The tray G, provided with the cap j, in combination with the pipe E, valve h, and pipes F F, substantially as and for the purposes set forth.

7. The tray G, formed with the troughs d d' 45 for holding the asbestos l, and with the perforated ridges or swells e e, substantially as and for the purposes set forth.
